CLAIM

The ornamental design for a correction roller, as shown and described.

DESCRIPTION

FIG. 1 is a top left rear perspective view of the correction roller shown with the cap in closed position according to our new design;

FIG. 2 is a left elevation view thereof;

FIG. 3 is a right elevation view thereof;

FIG. 4 is a top plan view thereof;

FIG. 5 is a bottom plan view thereof;

FIG. 6 is a front elevation view thereof; and

FIG. 7 is a rear elevation view thereof.

FIG. 8 is a top left rear perspective view of the correction roller of FIG. 1 shown without the cap for completeness of illustration;

FIG. 9 is a left elevation of FIG. 8;

FIG. 10 is a right elevation view of FIG. 8;

FIG. 11 is a top plan view of FIG. 8;

FIG. 12 is a bottom plan view of FIG. 8;

FIG. 13 is a front elevation view of FIG. 8; and,

FIG. 14 is a rear elevation view of FIG. 8;

The broken line showing of the elements of the correction roller is for the purpose of illustrating portions that form no part of the claimed design.
